REFUSE DESTRUCTOR

William James Bulgin, Worcester, England, assignor to Heenan & Froude Limited, Worcester, England

Application October 14, 1931. Serial No. 563,800

2 Claims. (Cl. 110—8)

This invention relates to improvements in furnaces for the consumption of low grade fuel, refuse and similar material.

In grates for such purpose it is usual to provide means such as a pusher or block actuated by a hydraulic ram or the like for removing the clinker and other residue from the grate so that it will fall into a chute arranged at the front of the furnace which delivers it to a conveyor or other means for transporting it away from the furnace.

According to the present invention a dumping grate is pivotally mounted at the front of the fixed grate on to which the clinker or other residue is pushed by the pusher or block and this dumping grate is connected by a system of levers with the pusher or block so that when the latter is in its rearward position the dumping grate will be prevented from pivoting but when it is moved forward the dumping grate will fall and the residue will be discharged into the chute; the return movement of the pusher block restoring the dumping grate to its horizontal position.

The invention will be described with reference to the accompanying drawing:—

Fig. 1 is a transverse section through the furnace.

Fig. 2 is a transverse section showing an alternative method of connecting the dumping grate to the pusher block.

The furnace is constructed with a fixed grate A over which a pusher block B can be moved by any mechanical means such as a hydraulic or pneumatic ram C arranged to push the residue off the grate. In the drawing the ram C is shown supported on the top of the duct D which supplies the air for the combustion of the fuel in the furnace but the ram may be supported in any other suitable way.

The dumping grate E is hinged or pivotally mounted on the rod a at the front of the fixed grate A. It is formed with one or more downwardly projecting lugs or brackets e to each of which is pivotally connected one end f of a link F, the other end f' of which is pivotally connected to the lower end g of a two armed lever G.

In the construction shown in Fig. 1 the lever G is fulcrumed at g¹ on a stationary part of the furnace. The upper arm g² of the lever G engages with a runner b on the pusher block B which prevents movement of the lever G when the block B is in its rearward position i. e. the position shown in full lines in the drawing.

Any number of lugs or brackets e may be em-

ployed according to the size of the grate so as to prevent sagging thereof.

In the construction shown in Fig. 2 the lever G is fulcrumed on a rocking link or arm G¹ and the upper arm g² of the lever G is directly connected to the pusher block B at b¹ so that the block B positively controls the movement of the dumping grate E in both directions.

As shown in the drawing the link F is preferably made in two parts, the end f being adapted to be moved in relation to the end f' by the nut f² so that the effective length of the link can be adjusted or varied.

A stationary drying hearth H may be arranged to cover the pusher block B when the latter is in its backward position and the refuse or other fuel is fed on to the drying hearth H through the feed opening K at the top of the furnace. The drying hearth may however be omitted when not required and the side wall of the furnace line up with the front end of the pusher.

The delivery chute L to receive the residue discharged by the dumping grate is arranged below the latter and is preferably closed by a pivoted door L¹ operated by a handle l¹ so that when the furnace is operating under pressure, the pressure can be maintained therein. The chute L may deliver the residue to a conveyor or other known device for transporting it away from the furnace.

When it is desired to remove the residues from the furnace the ram C is operated and causes the pusher block B to move over the grate A from the position shown in full lines on the drawing to that shown in dotted lines. The movement of the pusher block B pushes the residue on to the dumping grate E. In the arrangement shown in Fig. 1 the forward movement of the pusher block B moves the runner b out of engagement with the arm g² of the lever G so that the latter is no longer prevented from moving about its pivot g¹ to release the dumping grate E and consequently the weight of the dumping grate E and the residue thereon causes it to swing down into the vertical position shown in dotted lines when the link F and lever G will occupy the positions also shown in dotted lines. The residue is thus discharged into the chute L and can be released therefrom by the opening of the door L¹.

On the return movement of the pusher block B the runner b engages the arm g² of the lever G and moves the latter over into its original position and this movement causes the dumping grate E to be raised into the horizontal position in which it is maintained until the pusher block B is again operated and the runner b again

moved away from the arm g^3 of the lever G to release the dumping grate.

The action of the arrangement shown in Fig. 2 is similar to that above described except that 5 the movement of the pusher block B directly controls the movement of the dumping grate E, the rocking link G^1 oscillating about its pivot to allow of the necessary movement of the fulcrum of the lever G.

10 What I claim as my invention and desire to protect by Letters Patent is:—

1. A furnace for the consumption of low grade fuel, refuse and similar material comprising in combination a fixed grate, a dumping grate pivoted to the front thereof, a pusher block for pushing the residue off the fixed grate on to the dumping grate, a ram operating the pusher block, a chute below the dumping grate to receive the clinker discharged therefrom, a link pivotally connected at one end to the underside of the dumping grate, a lever pivotally connected at one end

to the other end of the link, and at its other end to the pusher block and an arm pivotally connected at one end to the furnace and at the other to a point substantially midway along the lever to positively connect the dumping grate with the 80 pusher block.

2. A furnace for the consumption of low grade fuel refuse and similar material comprising in combination a fixed grate, a rod extending transversely of the fixed grate at the front end thereof, a dumping grate pivoted on the rod, a pusher block for pushing the residue off the fixed grate on to the dumping grate, a ram operating the pusher block, a link pivotally connected at one end to the underside of the dumping grate, a lever 85 connected to the opposite end of the link, an arm on which the levers are mounted and projections on the pusher block engaging the pivoted lever to cause the movement of the pusher block to operate the dumping grate. 90
